SAFETY RAZOR

Victor B. Nelson, Rockford, Ill.

Application March 13, 1944, Serial No. 526,197

7 Claims. (Cl. 30—72)

This invention relates to safety razors of the type in which a flexible blade is bent and clamped against the guard by turning a screw element on the handle. It is known that by backing off the blade edge slightly relative to the guard an improved cutting action is obtained with such razors. The degree of such adjustment must however be gauged very accurately in order to preserve the safety character of the razor.

The primary object of the present invention is to provide a safety razor incorporating a novel mechanism by which the backing off adjustment above referred to may be gauged very accurately by the sense of feeling and by which the adjustment will be preserved in the subsequent use of the razor.

The invention also resides in the novel construction and arrangement of the gauging means which facilitates manufacture and ease and reliability of operation.

Other objects and advantages of the invention will become apparent from the following detailed description taken in connection with the accompanying drawing, in which

Figure 1 is a perspective view of a safety razor embodying the present invention.

Fig. 2 is a longitudinal section.

Fig. 3 is an exploded fragmentary perspective view of the handle construction.

Fig. 4 is a view similar to Fig. 3 showing a modification.

The razor shown for purposes of illustration is of the so-called Gillette type in which a flexible double edge blade 5 is bent around an arcuate guard 6 rigid with one end of a tubular handle 7. The blade is flexed and held against the guard by clamps 8 pivoted at 9 on a carrier 10 that may be shifted endwise of the handle to clamp or release the blade. Such actuation is effected by a rod 11 slidable in the handle 7 and moved endwise by turning a nut 12. The latter is journaled in the remote end of the handle and threads onto the end of the rod 11, a key 13 serving to hold the nut and handle against endwise movement. Thus, by tightening the nut, the blade is bent into the operative position shown. As the nut is turned reversely and loosened, the blade edge is permitted to spring back away from the guard, and eventually the clamps 8 are swung sufficiently to release the blade.

The present invention contemplates the provision of means releasable in response to the manual application of a turning movement to the nut 12 and operable to permit angular adjustment of the nut in fine increments the num-

ber of which may be sensed readily during turning. Herein this means includes a spring loaded detent 14 carried by a thumb piece or knob 15 on the nut 12 and coacting with surfaces 16 on the handle to hold the nut releasably in a plurality of well defined positions of angular adjustment. The surfaces 16 in the present instance constitute the walls of grooves 22 of V-shaped cross section extending along the handle and milled in the end 17 thereof. This end is of reduced diameter so as to be received in the end of the knob 15 which also receives the projecting end of the nut 12 and is secured to the latter as by a cross-pin 18.

15 In the present instance, the detent comprises a small ball 19 disposed in a hole 20 in the bottom 21 of an external groove 23 which is formed near the inner end of the knob 15. The diameter of the ball is somewhat greater than the thickness of the knob at the bottom surface 21 so that one side of the ball may seat in one of the grooves 22 while the other side projects outwardly from the surface 21.

The ball 19 is pressed inwardly by a novelly arranged spring 24 comprising, in the present instance, several turns of resilient wire wound into a tight helical coil somewhat smaller in diameter than the bottom surface 21 and having its convolutions disposed close to each other. The axial length of the coil is such as to substantially fill the space between the side walls of the groove 23 and thereby engage the ball 19 at all times. The resiliency of the coil in tending to contract urges the ball radially inwardly causing the ball to seat firmly in any one of the recesses 22 with which the ball is brought into register. At the same time, the ball may be cammed outwardly as permitted by expansion of the spring coil so as to enable the knob 15 to be turned and present the ball detent to different ones of the recesses 22. By virtue of the coiled character of the spring, a substantial force may be applied to the ball without danger of the spring fatiguing in service use. At the same time the arrangement is compact and the construction of the knob to accommodate the spring is simple and inexpensive to manufacture.

The spring actuated detent may, if desired, be constructed as shown in Fig. 4 comprising a piece 50 26 of resilient wire lying in a slot 27 that extends longitudinally of the knob 15. The straight end 28 of the wire is forced into the narrow end of the slot and is retained with a press fit. The other end of the wire is free to move radially in the slot, and its hooked end 29

is urged under the spring effect inwardly against the peripheral surface of the end 17 so as to enter one of the grooves 22 whenever the two are in register. Preferably, the upper end of the knob is formed with a head 30 corresponding in cross section to the head 29 of the detent wire. The wire being of rounded section and the walls 16 flaring outwardly, it will be apparent that the detent will ride out of the groove automatically as an incident to the application of a small torque to the knob 15. Yet, when the detent is seated in one of the grooves, the knob is held quite firmly against accidental turning.

The grooves 22 are spaced uniformly around the handle and the spacing is such that turning of the detent from one slot to the next will, in the final clamping of the blade, effect a movement of approximately .001 of an inch of the blade edge relative to the guard. Accordingly, to adjust the razor to the individual user, the knob 15 is, after insertion of a blade, first turned as far as possible, that is, until the blade is clamped solidly against the guard. Then, the knob is slowly turned reversely to back off the blade edge the desired distance from the guard. The user will feel each entry of the ball 19 into one of the grooves 22 and thereby may gauge accurately the degree of adjustment so as to space the blade away from the guard the distance best suited to give the desired cutting action.

It will be observed that the backing off adjustment may be made quickly and conveniently and may be sensed by feeling. The adjustment once made, it is retained effectively throughout the subsequent use of the razor and yet may be reestablished readily following loosening of the blade for cleaning of the razor or replacement of the blade.

This application is a continuation-in-part of my co-pending application Serial No. 446,555, filed June 11, 1942.

I claim as my invention:

1. In a safety razor, the combination of a handle, a screw member telescoping with the end of said handle and manually rotatable relative thereto, a slot extending longitudinally of said screw member, a piece of resilient wire disposed in said slot with one end portion fastened to the screw member and the other end portion bent reversely and urged against the overlapped portion of said handle, and formations annularly spaced around said handle and engageable with said reversely bent portion to hold said screw member in different angular positions while permitting yielding of said wire and when a turning torque is applied manually to the screw member.

2. In a safety razor, the combination of a hollow handle, blade clamping means carried by said handle, means for actuating said blade clamping means to clamp and release a blade and including a screw member telescoping within the free end of said handle and manually rotatable relative thereto, means for restraining the screw member against movement longitudinally of the handle, a piece of resilient wire mounted on and concealed in said screw member and having a detent portion bearing against the overlapped portion of said handle, and formations formed on and annularly spaced around said handle and engageable with said detent portion to hold said screw member in different angular positions, said wire being yieldable automatically in response to the application of

a manual turning torque to said screw member in adjusting the blade within said clamping means.

3. In a safety razor, the combination of a handle, blade clamping means carried by said handle, means for actuating said blade clamping means including a screw member telescoping within a recess provided in the free end of said handle and manually rotatable relative thereto, means restraining the screw member against longitudinal movement, means providing a series of outwardly opening V-shaped notches annularly spaced around the exterior of said handle and concealed within an overlying portion of said screw member, and a spring actuated detent element carried by said screw member and yieldingly urged against the underlying portion of said handle, the walls of said notches and the surface of said element being shaped to permit yielding of the element automatically in response to the manual application of a turning movement in either direction to said screw member in adjusting said blade clamping means.

4. In a safety razor, the combination of a supporting member, blade clamping means carried by said member, means for actuating said blade clamping means including a screw member rotatable relative to said supporting member and held against endwise movement, a series of formations on one of said members annularly spaced around the latter, and a spring actuated detent mounted on the other member and yieldingly urged into engagement with said formations to normally hold the screw member against turning, said formations and detent being shaped to yield automatically under the manual application of a turning torque to said screw member in either direction whereby the user may feel the interengagement of the detent and each successive formation to sense the relative position of the blade and clamping means.

5. In a safety razor, the combination of a supporting member, blade clamping means carried by said member, means for actuating said blade clamping means including a screw member rotatable on said supporting member and held against axial movement relative thereto, a series of formations on said supporting member annularly spaced around the latter, said screw member having a hole therein opposite said formations, a ball disposed in said hole, and a resilient wire coiled around said screw member and yieldably urging said ball into engagement with said formations to normally hold the screw member against turning, said formations and ball being shaped to yield automatically under the manual application of a turning torque to said screw member in either direction.

6. In a safety razor, the combination of a supporting member, blade clamping means carried by said member, means for actuating said blade clamping means including a screw member rotatable on said supporting member and held against endwise movement relative thereto, a series of formations on said supporting member annularly spaced around the latter, a resiliently expandable wire ring contracted around said screw member opposite said formations, and a detent mounted in said screw member for radial movement relative thereto and engaged on one side by said ring and on the opposite side by said member and formations, said formations and detent being shaped to expand said ring automatically under the manual application of a turning torque to said screw member in either direction.

whereby the user may feel the interengagement of the detent and each successive formation to sense the relative position of the blade and clamping means.

7. In a safety razor, the combination of a supporting member, blade clamping means carried by said member, means for actuating said blade clamping means including a screw member rotatable relative to said supporting member and held against endwise movement, a series of formations on one of said members annularly spaced around the latter, a spring actuated detent element mounted on the other member and engage-

able with said formations, and a resiliently expandible and contractible coil of wire engaging said element and yieldably urging the same into engagement with said formations to normally hold the screw member against turning, said formations and detent element being shaped to yield automatically under the manual application of a turning torque to said screw member in either direction whereby the user may feel the interengagement of the detent and each successive formation to sense the relative position of the blade and clamping means.
